METHOD OF FORMING DIE CAST PRODUCTS

Louis H. Morin, Bronx, N. Y.

Original applications December 28, 1943, Serial Nos. 515,196, 515,197, and 515,198. Divided and this application June 23, 1945, Serial No. 601,154

12 Claims. (Cl. 18—55)

1

This invention relates to the production of various articles of manufacture such, for example, as hinges, buckles, as well as swivel jointed bodies. More particularly, the invention deals with a method of producing articles of manufacture of the type and kind defined, wherein each article is composed of two die cast parts, one part being cast with a socket or bearing portion and the other part cast with a pin rod or pintle portion formed directly in the socket or bearing portion of the first part in providing relative swinging or rotatable movement of the parts one with respect to the other. The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a diagrammatic face view of one of the dies employed in forming a pair of hinge leaves showing one method of forming and inter-casting said leaves.

Fig. 2 is a section on the broken line 2—2 of Fig. 1.

Fig. 3 is a perspective view of a hinge detached by a trimming operation.

Fig. 4 is a view similar to Fig. 1 showing another adaptation of the invention.

Fig. 5 is a diagrammatic face view of one of the dies which I employ in producing another article of manufacture such, for example, as a buckle.

Fig. 6 is a section on the line 6—6 of Fig. 5.

Fig. 7 is a perspective view of a complete buckle illustrating a use thereof with parts of a belt in dot and dash lines.

Fig. 8 is a diagrammatic face view of a pair of dies employed to form swivel coupled bodies.

Fig. 9 is a section on the broken line 9—9 of Fig. 8; and,

Fig. 10 is a detailed view of an article made from the dies shown in Fig. 8 with part of the construction broken away and in section.

This application is a division of my prior applications Serial Numbers 515,196 now Patent No. 2,569,862; 515,197 now abandoned and 515,198 now abandoned filed December 21, 1943.

In constructing hinges, buckles and swivelled bodies of the type herein illustrated, it is usually customary to provide independent pins, rods or shaft portions for arrangement in the bearings of parts of these articles to couple the articles together. It is the purpose of my invention to

2

materially simplify and economize on the production of articles of manufacture of this kind by forming the pintles or pins or what may be termed pivot portions as an integral portion of one of the parts of the article and to form this pintle or pin directly in the socket or apertures of the bearing portion or portions of the other part in permanently uniting said parts. In some instances, for example, in forming hinges, my improved method also eliminates exposure of pintle or pin ends and formation of heads thereon.

In Figs. 1 and 2 are shown at 10 and 11 the two die parts employed for producing the dual die cast body 12 in the impression chamber or cavity 13 formed on the parting line of the die parts, as will clearly appear from a consideration of Fig. 2. The upper part of the cavity 13, as seen in the drawing, is adapted to form one leaf part 14, which comprises a rectangular plate having spaced countersunk screw apertures 15 therein. At one edge of the plate are spaced pintle bearings 16 disposed inwardly of side edges of the leaf 14. On the completed hinge the bearings 16 are adapted to be arranged in the spaced recesses 17 formed between the pintle bearings 18 of the leaf 19.

The leaf 19 is also in the form of a rectangular plate having the pintle bearings 18 at one edge thereof. Countersunk apertures 20 are also formed in the leaf 19 to receive the screws or other fasteners. In forming the leaves 14, 19, these leaves are simultaneously cast in the cavity 13 by injection of heated casting material from a discharge nozzle 21 through a gate passage 22 into the cavity. In the casting operation, the plate portions of the leaves 14, 19 are joined by connecting webs 23 which are severed in the trimming operation. This separates the two leaf parts which are cast as a unit but, at the same time, forms pairs of leaves 14, 19 that are permanently united and pivotally coupled by reason of the integral pintle pin portions 24 on the leaf 19 being cast in the apertures 25 of the bearings 16 or in the bushings 26 arranged in said apertures.

The unit casting 12 is formed on a core pin 27 supported in the upper portion of the dies and, upon which, the bushings 26, as inserts, are arranged. Thus after the cast unit 12 is formed, the dies are separated and the cast unit is left suspended on the core 27. This core is then moved downwardly to position the leaf part 14 of the first cast unit in an impression 28 at the lower portion of the dies, after which the dies are partially closed, the core pin 27 stripped

from the first casting, then returned to its original position and other inserts 26 arranged on the core pin and a second cast unit formed. In this last operation, the pintle pin portions 24 are cast within the bearings 16.

It will appear from a consideration of Fig. 2 of the drawing that the die 11 has pin portions 29 which extend across the cavities and enter recesses 30 in the die in forming the countersunk apertures 15, 20. The die 11 will also have at least one pin 31 in the cavity 28 to engage at least one of the pre-formed countersunk apertures of the leaf 14 to retain said leaf against displacement when the dies are in the partially closed position and in the operation of stripping the core pin, as above described.

In Fig. 4 of the drawing, I have shown another method of forming hinges of the kind under consideration which consists in forming one leaf 32 at one side of a pair of dies 33 and the other leaf 34 at the other side thereof, the leaves being in spaced relationship to each other and joined through a gate 35, so that these leaves are simultaneously cast in the injection of heated casting material from a nozzle 36.

The leaf 32 has at one side edge thereof pintle bearings 37, similar in all respects to the bearings 16; whereas the leaf 34 has at one side thereof spaced bearings 38 similar to the bearings 18. Between the bearings 38 are recesses 39 for receiving the bearings 37 and are, thus, similar in this respect to the recesses 17. In other words, while the brief description of Figs. 1 and 2 has been applied to Fig. 3, it will be understood that the resulting hinge formed by the method shown in Fig. 4 will be the same as the hinge shown in Fig. 3. From this standpoint, further details of construction of the leaves 32, 34 will be omitted.

In Fig. 4, a vertical core pin 40 is employed and this core pin, in addition to extending through the bearings 37, also extends to and supports part of the gate 35, as indicated at 41. The purpose of this is to avoid any tendency of severing the two leaves 32, 34 in shifting them, by the core pin 40, from the cast position to the lowered position where the leaf 32 enters the impression forming the leaf 34.

After stripping the core pin 40 from the cast unit comprising the two leaves 32, 34, with the dies in a partially closed position, the core is returned to its normal position and the next successive cast unit is formed and, in this operation, the pintle portions 42 which join the bearings 38 will be formed within the bearings 37, thus pivotally and hingedly uniting the pre-cast leaf 32 with the cast leaf 34, the same as in uniting the leaf 14 with the leaf 19.

From the foregoing, it will be understood that, in both methods of procedure, a pair of hinge leaves are formed in each casting operation and one leaf is united with its pre-cast companion leaf. In both cases, in the initial casting operation or when the first of a series of leaf units are formed, a suitable plug, preferably patterned along the lines of the leaves 14, 32 will be arranged between the dies and, by making these of separate parts split along the line of the pintle, they may be removed and thereafter the operation will be continuous. The assembled hinges may be cast in units of predetermined length or they may be trimmed shortly after the cast assemblage to form the independent unit hinges comprising the leaves 14, 19, or the butts 32, 34.

In both forms of construction, it will be apparent that the dies will have suitable portions,

as at 43, fitting in the recesses 17, 39 and around the bearings 16, 37.

In referring to the use of heated casting materials, it will be understood that the hinge leaf parts may be formed from suitable metals or metal alloys or from different plastic materials. When metals are used and when it is desired to employ the bushings, these bushings may be composed of hard fibrous material or suitable bearing metals and plastics. Either harder plastics, metals or fibrous materials can be employed.

It will, of course, be apparent that the shape or contour of the attaching plates of the leaves may be characterized in any desired manner. Further, the combination of interengaging bearings may be modified and, in fact, the general structure of the pintle or pivot portion of the leaves may be made to suit the type of hinge employed in the hinge coupling desired between two members.

In all instances, however, the last cast portion in producing the assembled unit will be the internal bearing portion of the coupling in order to benefit by the shrinkage of this cast portion in producing the resulting free and yet firm bearing action between the relatively movable members. In the present illustrations, the inner or last cast portion is the pintles 24, 42. It will be understood that any means may be provided for supporting the bushings in proper position as inserts on the core pins. Slight frictional engagement with the pins would be sufficient.

In Figs. 5, 6 and 7 is shown another adaptation of my invention.

In Fig. 6 of the drawing are shown two substantially similar die parts 44, each having on the parting line or adjacent abutting surfaces 45 thereof impressions of the general contour seen in the face view of one of these dies, as illustrated in Fig. 5. The impression or cavity is divided into a hasp part 46 and a buckle part 47 to form in a single cast unit a hasp 48 and a buckle body or ring 49. These parts are joined by a common gate 50, into which heated casting material is injected from a suitable nozzle 51.

The dies 44 also have an impression or cavity 52 for receiving a portion of the hasp 48 of a pre-cast unit, when the latter has been moved into the lowered position through the medium of a core pin 53 which extends through the looped or ringed end 54 of the hasp and also into part of the gate 50 adjacent the ring body 49. In a simple form of the invention, the core 53 will form the opening or aperture of the ring 54. However, in the present illustration, a bushing 55 is arranged on the core pin 53 so as to bush the aperture or opening in the ring end 54 of the hasp. When the hasp is composed of metal, the bushing may be of a harder or suitable bearing metal or of fibrous material. Whereas, if the hasp is composed of a plastic die cast material, the bushing may be of metal, fiber or another plastic material having suitable bearing properties.

The ring body 49 of the buckle in the construction shown, comprises a loop having a straight cross-head or bearing portion 56 provided at opposite sides of the ring portion 54 of the hasp with annular collars 57 to position the hasp centrally of the cross-head 56. It will appear from a consideration of Fig. 5 of the drawing that the dies 44 are cut out, as seen at 58, to disengage from the gate portion 50 when a pre-cast unit is in its lowered position. When the

unit is still further removed from the dies, the hasp of one unit and the loop body of the adjacent unit to which the hasp unit is attached by a gate may be severed by a trimming operation and, thus, complete buckles will be formed with the hasp 48 as an integral part of the ring body 49 and free to swing or rotate thereon.

It will be understood that the resulting buckle product is formed from the hasp of one unit casting and the ring body of the next successive casting. By producing the buckle in this manner, the pintle portion 59 of the cross-head 56 and between the annular beads 57 will shrink away from the bushing 55 sufficiently to provide a free but yet snug mounting of the hasp on the pintle 59. In the operation of forming the successive castings, it will be understood that the core 53 is stripped from a cast unit when in its lowered position and when the dies are in the partially closed position. When the core 53 is returned to normal position, the dies are again closed and the next successive cast unit is formed.

In the accompanying drawing a very simple and more or less conventional type of buckle has been shown for the purpose of illustrating one adaptation and use of the invention. It will be apparent, however, that buckles or similar articles of manufacture employing two relatively movable or swingable parts can be produced in accordance with the method here defined. With buckles as illustrated, an ordinary belt may be readily and practically used in connection therewith, as indicated at 60 in dot and dash lines in Fig. 7 of the drawing.

Figs. 8, 9 and 10 show a further adaptation of my invention and, in Fig. 10, of the drawing is shown an article of manufacture comprising a ring or loop 61 having an enlarged end portion 62, in which is a tapered socket or aperture 63. In some instances, the socket or aperture 63 may have a bushing, as at 64, of a material providing a suitable bearing surface and the required wear. The bushing 64, when the body 61 is composed of cast metal, will be of a harder or suitable bearing metal, or of fibrous material. Whereas, when the body 61 is composed of plastic material, the bushing may be composed of suitable metal, fiber or a different plastic.

At 65 is shown a pin member having a tapered shank 66 fitting in the socket 63 or the bushing 64 therein. At one end of the shank 66 is an enlargement in the form of a ball member 67 and at the other end is a ring or eye 68. The ring or eye 68 joins the wide end of the shank in an enlarged annular collar portion 69. The ball end 67 and collar 69 retain the loop or ring body 61 against displacement from the pin member 65.

In producing the article or product unit as seen in Fig. 10 of the drawing, a pair of similar die members 70 are employed and adjacent abutting surfaces of these die members will have cavities 71 and 72 for forming the respective parts 61 and 65 as a single cast unit. These parts 61 and 65 are joined in the gate portion comprising the web 73 and the lateral extension 74. At 75 is shown a nozzle, through which heated casting material is adapted to be pressure injected into the cavities 71, 72 through the gates 73, 74 as will be apparent.

In forming the unit comprising the parts 61 and 65, the bushing 64 is arranged upon the tapered end 76 of a core pin 77. When the bushing 64 is not employed, the tapered end 76 will be made to fit directly in the aperture or socket

63 of the part 61, which socket, in such instances, would have a plain wall structure.

From the foregoing, it will be apparent that when the unit casting comprising the parts 61 and 65 is formed, it will be formed about the core pin 77 and, after formation, the dies will be separated and the unit casting moved into the lowered position, in which position the part 61 will register with a partial cavity 78 in the dies 70, conforming to the general outer contour of the upper portion of the part 61, as will readily appear from a consideration of Fig. 8 of the drawing. In other words, the cavity 78 registers with the cavity 72, so that, in forming the next successive casting, after the core 77 has been returned to its original position, the pin member 65 will be cast within the socket of the loop part 61 of the pre-formed casting.

In the initial casting operation, a dummy, substantially similar to the part 61, will be used in the cavity 78 and preferably composed of split parts to facilitate detachment from the pin part 65 after the first casting has been formed. In production, cut off loop bodies 61 can be used as such dummies and saw cut through the socket portion 62 thereof.

From the foregoing, it will be readily apparent that, in producing the article or product, as seen in Fig. 10, the member or part 61 is formed from one cast unit, whereas the pin or member 65 is formed from the next successive cast unit in a continuous series of successive castings.

In some instances, where it is desirable to construct a continuous chain-like structure, instead of trimming off the gate portion 73 as would be the case in the present teachings, these gate portions, as at 73, may be stoutly constructed to form a strong coupling between the ring 78 and the end of the loop body 61 and the part 74 of the gate may be trimmed from the part 73.

In the above described operation of feeding the cast unit downwardly to bring the part 61 in registering position with the impression 78, the dies are moved into a partially closed position in the operation of stripping the core 77 from this lowered cast unit preparatory to returning the same as to its initial position, as shown in Figs. 8 and 9. In this operation, the member 79 on one of the dies engages the loop part 61 in supporting the casting against the pull of the core. The said die also includes portions 80, note Fig. 8, which maintains the casting in position, preparatory to closing the dies for the next successive casting operation.

In forming the articles of manufacture of plastic materials, different nozzles or nozzles containing plastic materials of different colors may be intermittently moved into registering position with the gate 74, so that, in the resulting castings, the part 61 may be composed of one colored plastic and the part 65 of another colored plastic.

It will also be apparent that the shape and contour of the separate parts 61 and 65 may be varied in many ways to adapt these parts to the many uses of swivelled coupled parts of the kind under consideration. It will also be apparent that my invention is not limited to the use of a tapered shank portion such as illustrated in the present disclosure of the invention.

Having fully described my invention, what I claim is new and desire to secure by Letters Patent is:

1. The method of forming articles of manufacture of the class described, which comprises simultaneously die casting a pair of members be-

tween relatively movable dies, forming on one member a socket portion and on the other member a pin portion, separating the dies, then moving said members collectively and positioning them so that said socket containing member projects into the die cavity wherein the pin containing member is formed, then closing the dies and forming a second pair of said members wherein the pin portion of the pin containing member of said second pair is cast within the socket portion of the socket containing member of the first pair to movably couple the latter two members, said movably coupled members being freely movable with respect to each other by virtue of the shrinkage of said pin portion within said socket portion upon the cooling of the pin portion.

2. The method of forming articles of manufacture of the class described, which comprises simultaneously die casting a pair of members between relatively movable dies and uniting said members together by means of gate portions, forming on one member a socket portion and on the other member a pin portion, separating the dies, then moving said socket and pin members collectively and positioning them so that said socket member projects into the die cavity wherein the pin member is formed, then closing the dies and forming a succeeding pair of socket and pin members wherein the pin portion of the pin member of said succeeding pair is cast within and through the socket portion of the socket member of the preceding pair to movably couple the latter two members, said movably coupled members being freely movable with respect to each other by virtue of the shrinkage of said pin portion within said socket portion upon the cooling of the pin portion, and trimming said gate portions to form movably coupled socket and pin members each comprising one member from one pair of simultaneously cast members and a member from the next succeeding pair of simultaneously cast members.

3. The method of forming articles of manufacture of the class described, which comprises simultaneously die casting a pair of members between relatively movable dies, forming on one member a socket portion and on the other member a pin portion, separating the dies, then moving said socket and pin members collectively and positioning them so that said socket member projects into the die cavity wherein the pin member is formed, then closing the dies and forming a succeeding pair of socket and pin members wherein the pin portion of the pin member of said succeeding pair is cast within and through the socket portion of the socket member of the preceding pair to movably couple the latter two members, said movably coupled members being freely movable with respect to each other by virtue of the shrinkage of said pin portion within said socket portion upon the cooling of the pin portion, and casting the socket member of each pair around a bushing to form a liner for the socket thereof.

4. The method of forming movably and permanently coupled die cast members, which comprises forming a die cast unit between relatively movable dies, wherein said unit comprises one member having a pair of socket portions formed around a core pin and another member having spaced recesses within which are arranged pintle portions, separating the dies, then feeding said unit relatively to the dies to position the socket portions of the first mentioned member in aline-

ment with the pintle forming portions of said dies, partially closing the dies and stripping the core pin from said unit and returning the same to its original position between the dies, then closing the dies and forming another cast unit similar to the first unit, and casting the pintle portions of the second unit within socket portions of the first mentioned member of the first unit to movably and permanently couple one member of each unit.

5. The method of forming die cast hinges having interfitting pintle bearings on the leaves thereof, which comprises die casting a successive series of leaf units between relatively movable dies, forming the pintle bearings of one of the units around a core pin to produce sockets therein forming the other leaf of said unit in spaced relation to the first named leaf and joined through a gate portion, forming between the bearings of the second leaf of said unit pintle portions integral with said leaf, separating the dies and shifting the first unit by said core pin to bring the first leaf in registering position with the cavity of the die which formed the second leaf of the cast unit, stripping the core pin from the first cast unit and returning it to original position, and then forming the next successive cast unit with the pintle portions of the second leaf of said unit cast within the sockets in the pintle bearings of the leaf of the first unit.

6. The method of forming die cast hinges having interfitting pintle bearings on the leaves thereof, which comprises die casting a successive series of leaf units between relatively movable dies, forming the pintle bearings of one of the units around a core pin to produce sockets therein forming the other leaf of said unit in spaced relation to the first named leaf and joined through a gate portion, forming between the bearings of the second leaf of said unit pintle portions integral with said leaf, separating the dies and shifting the first unit by said core pin to bring the first leaf in registering position with the cavity of the die which formed the second leaf of the cast unit, stripping the core pin from the first cast unit and returning it to original position, then forming the next successive cast unit with the pintle portions of the second leaf of said unit cast within the sockets in the pintle bearings of the leaf of the first unit, and then trimming the successive castings to remove the gates therefrom in forming hinges, each comprising one of the leaves of successive cast butt units.

55. 7. The method of forming die cast hinges having interfitting pintle bearings on the leaves thereof, which comprises die casting a successive series of leaf units between relatively movable dies, forming the pintle bearings of one of the units around a core pin to produce sockets therein forming the other leaf of said unit in spaced relation to the first named leaf and joined through a gate portion, forming between the bearings of the second leaf of said unit pintle portions integral with said leaf, separating the dies and shifting the first unit by said core pin to bring the first leaf in registering position with the cavity of the die which formed the second leaf of the cast unit, stripping the core pin from the first cast unit and returning it to original position, then forming the next successive cast unit with the pintle portions of the second leaf of said unit cast within the sockets in the pintle bearings of the leaf of the first unit, then trimming the successive castings to remove the gates

therefrom in forming hinges, each comprising one of the leaves of successive cast butt units, forming countersunk apertures in each of said leaves, and arranging bushings on said core pin in providing bushing inserts in the socket portions of the bearings of the first leaves in each cast unit.

8. The method of forming buckles of the class described, which comprises die casting a buckle body and a hasp member as a single casting unit between relatively movable dies, forming one end of the hasp around a core pin to form a ring-like socket at said end of the hasp, forming a cylindrical bearing portion on the buckle body, then separating the dies and moving the casting to position the socket portion of the hasp in alignment with the cylindrical bearing forming portion of said dies, then removing the core pin and returning the same to the normal position thereof, then closing the dies, and forming the next successive casting with the bearing portion of the second casting formed in the socket portion of the hasp of the first casting.

9. The method of forming buckles of the class described, which comprises die casting a buckle body and a hasp member as a single casting unit between relatively movable dies, forming one end of the hasp around a core pin to form a ring-like socket at said end of the hasp, forming a cylindrical bearing portion on the buckle body, then separating the dies and moving the casting to position the socket portion of the hasp in alignment with the cylindrical bearing forming portion of said dies, then removing the core pin and returning the same to the normal position thereof, then closing the dies, forming the next successive casting with the bearing portion of the second casting formed in the socket portion of the hasp of the first casting, joining the buckle body and hasp of each casting in a gate portion, and then trimming the gate portions to form buckles each comprising a hasp of one casting and a buckle body of the next successive casting.

10. The method of forming buckles of the class described, which comprises die casting a buckle body and a hasp member as a single casting unit between relatively movable dies, forming one end of the hasp around a core pin to form a ring-like socket at said end of the hasp, forming a cylindrical bearing portion on the buckle body, then separating the dies and moving the casting to position the socket portion of the hasp in alignment with the cylindrical bearing forming portion of said dies, then removing the core pin and returning the same to the normal position thereof, then closing the dies, forming the next successive casting with the bearing portion of the second casting formed in the socket portion of the hasp of the first casting, joining the buckle body and hasp of each casting in a gate portion, and then trimming the gate portions to form buckles each comprising a hasp of one casting and a buckle body of the next successive casting.

ond casting formed in the socket portion of the hasp of the first casting, joining the buckle body and hasp of each casting in a gate portion, then trimming the gate portions to form buckles each comprising a hasp of one casting and a buckle body of the next successive casting, and forming the socket portion of the hasp around a bushing insert supported on said core in producing on the resulting buckle a liner for said hasp.

- 10 11. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
- 15 12. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
- 20 13. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
- 25 14. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
- 30 15. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
- 35 16. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
- 40 17. The method of forming pairs of members swivelly coupled together, which comprises die casting a pair of united members on a core arranged between abutting surfaces of relatively movable dies with a portion of one of said members embracing the core to form an apertured portion, separating the dies, moving the casting by moving said core into a different position between the dies, stripping the core from the casting, again closing the dies, and then forming a next successive casting which is a duplicate of the first, with one member of said next successive casting cast within and through the apertured portion of said first-mentioned member of said re-positioned first named casting.
